Patented May 21, 1918.

UNITED STATES PATENT OFFICE.

MAX MAAG, OF ZURICH, SWITZERLAND.

GEAR-CUTTING MACHINE.

1,266,839.

Specification of Letters Patent. Patented May 21, 1918.

Application filed August 30, 1916. Serial No. 117,705.

To all whom it may concern:

Be it known that I, MAX MAAG, a citizen of the Republic of Switzerland, residing at Hardstrasse 219, Zurich, Switzerland, have invented certain new and useful Improvements in Gear-Cutting Machines; and I do hereby declare the following to be a full, clear, and exact description of the invention, such as will enable others skilled in the art to which it appertains to make and use the same, reference being had to the accompanying drawing, and to letters or figures of reference marked thereon, which form a part of this specification.

15 This invention relates to improvements in gear-cutting machines having a blank-carrier, which besides receiving during the cutting operation a successive rolling movement, consisting of a revolving movement and a longitudinal travel, carries out during the time outside the cutting operations, *i. e.*, between succeeding cutting operations some additional movements during which a multiple-tooth cutter of rack form has to be prevented from coming in contact with the teeth to be cut. In order to bring the cutting tool during said additional movements out of contact with the blank, the machine forming the subject-matter of my present invention has means adapted to swing said tool backward while the tool carrier is still moved. These means are then adapted to keep at the same time the tool out of reach of the blank until a new cutting operation is

35 restarted.

The hereinafter described construction is particularly adapted to be applied to gear-cutting machines working according to the rolling principle and having a central drum controlling the different movements of the machine and a reciprocating ram provided with a hinged tool holder. As this tool holder can be swung backward only during the upward movement of the ram, or while the ram is in its uppermost or lowest position I provide a construction in which the movement of the hinged tool holder, during the time outside the cutting operations, is initiated by said central control drum, while the releasing of this movement is effected by a shaft which may be driven either by the feed-shaft of the machine or a cam-disk shaft actuating the ram carrying the tool holder.

55 This invention will now be more particularly described with reference to the accom-

panying drawing, which illustrates a preferred form of the invention.

In this drawing:

Figure 1 is a side view partly in section 60 of the gear-cutting machine,

Fig. 2 is a section on the line A—B of Fig. 1,

Fig. 3 is a section on the line C—D of Fig. 1; 65

Figs. 4 and 5 are vertical sections through the ram carrying the hinged tool holder,

Fig. 6 is a rear view of a part of the machine and

Figs. 7 and 8 are sections on the line E—F 70 of Fig. 6 showing the parts in different working positions.

In carrying this invention into effect as shown in the drawing I provide a tool ram 2 adapted to reciprocate in the guidance 1 75 in the direction of the double arrow 43 (Fig. 1). A cam-disk 4 and a slide 3 transmit the movement of a constantly revolving shaft 5 to said ram 2. Shaft 5 is driven by the main driving shaft 5^a. To the ram 80 2 is hinged the clapper-box or tool holder plate 6 carrying the cutting tool 7 and adapted to oscillate in the direction of double arrow 40 (Fig. 5) about bolt 8. A spring 44 (Fig. 1) has the tendency to 85 swing said clapper-box 6 in a forward, that is, clockwise direction, while levers 9 and 10 (Figs. 3, 4, 5) may effect a backward oscillation of this clapper-box or plate 6. The lever 10 is fixed to a vertical shaft 11 90 (Figs. 3 and 1), which carries a toothed-wheel segment 12 (Figs. 2, 3) meshing with a toothed-wheel segment 13 fixed to a vertical shaft 14 (Figs. 1 and 2). To the lower end of this shaft 14 is fixed a lever 15 resting on the circumference of the cam-disk 4. The already mentioned spring 44 presses this lever 15 against cam 16, which extends over half the circumference of said disk 4, so that lever 15 causes, upon each revolution of the cam-disk shaft 5 during the cutting operation, an oscillation of the plate 6. Cam 16 is thereby arranged in such a manner that the hinged plate 6 is just swung backward, when the ram 2 is moved upward. 105 This oscillation of the plate 6 during the cutting operation has, however, nothing to do with the hereinbefore mentioned movement of this plate, which takes place during the time outside the cutting operation, *i. e.*, 110 between two succeeding cutting operations. During each backward oscillation of the

plate 6 brought about by cam 16 while the ram is moved upward, the tool holder is moved just to such an amount backward, that the cutting edge of the tool is prevented from touching the teeth of the blank, it not being necessary thereby to move the tool under all conditions beyond the outer diameter of the blank in order to bring it out of contact with said blank.

10. To lever 15 is also fixed a cam 17 acted upon by a shaft 18. The outer end 21 (Figs. 1, 7 and 8) of this shaft 18 has the form of a toothed rack which engages with a toothed-wheel segment 19. 20 denotes a lever rigidly connected to this segment 19. A rod 22 connects lever 20 to a lever 23. This lever 23 is formed integral with an arm 26 and it is loose on shaft 24 to which is fixed a disk 25. The latter is provided 25 on its circumference with a cam 27. Shaft 24 is oscillated during the cutting operation by an arm 46 operatively connected to the cam-disk shaft 5 by means of toothed wheels 47, 48 and a cam-disk 49. This arm 46 is moved 30 on each revolution of the disk 49 through an angle α (Fig. 7). Cam 27 referred to is adapted to move a lever 28 acted upon by a draw-spring 28^a connected at one end to a part formed integral with this cam and at 35 the other end to lever 23. A vertical rod 31 is also adapted to act upon said lever 28. 29 denotes a movable lever, which is adapted to keep arm 26 in its uppermost position. Said lever 29 is rigidly connected to a segment 30 and it is acted upon by a spring 30^a connected at one end to the frame of the machine. This segment 30 may be lifted by a ring 32 fixed to the rod 31, the lower end of which carries a roll 51 resting on the 40 central drum 33 having a cam 34. The drum 33 is moved in the direction of arrow 35 by a rod 36 fixed to a block adapted to move in the arm 46 and a disk segment 37 carrying a pawl 38, which engages with a 45 ratchet wheel 39 fixed to a shaft 39^a. A gearing 41 transmits the movement of this shaft 39^a to a shaft 42 (Fig. 8) to which is fixed said drum 33.

The hereinbefore described mechanism for 50 effecting an oscillation of the hinged tool holder between succeeding cutting operations works as follows:

As already mentioned, the backward swinging of the tool holder 6 is initiated by 55 the central drum 33. The cam 34 of the latter is arranged in such a manner, that its end is moved past roll 51 carried by rod 31 shortly before the cutting operation is completed. The rod 31 is then moved downward owing to the tendency of the spring 28^a connected to the cam 27 as well as to 60 the lever 23, to pull said cam 27 downward. Ring 32 fixed to shaft 31 is then also moved downward, so that the lever 29 acted upon 65 by spring 30^a and the segment 30 rigidly

connected to said lever 29 are oscillated to a small amount in a counter-clockwise direction. Owing to said downward movement of the shaft 31 the nose 50 of lever 28 is now able to engage disk 25. Upon the succeeding rotation of this disk 25 in a counter-clockwise direction corresponding to an upward movement of the ram, levers 28 and 23 are moved toward the left while rod 22 is moved downward, so that the toothed segment 19 effects a forward movement of shaft 18 (Fig. 8). Thus, lever 15 is also moved in a forward direction and the shafts 14 and 11 are moved in such a manner, that the hinged tool holder 6 is swung backward 70 and brought wholly out of reach of the teeth of the blank (Fig. 5).

In order to keep now the tool plate 6 in the inclined position shown in Fig. 5 until the next cutting operation is restarted it is necessary, that the spring 45 be prevented from moving the rod 18 in a backward direction until such a new cutting operation is restarted. This is effected by lever 29, which keeps the lever 26 in its uppermost 80 position (Fig. 8).

The moving back of the hinged tool holder 6 into its original position is again initiated by the central drum 33. Shortly before the cutting operation is restarted, the cam 34 of the revolving drum 33 is moved beneath roll 51 carried by the rod 31, so that the latter is lifted. The ring 32 of this rod 31 moves thereby the segment 30 in a clockwise direction, so that also lever 29 is moved toward the right. The spring 45 is now able to move rod 18 toward the right, while lever 23 and arm 26 are moved from the position shown in Fig. 8 into that shown in Fig. 7. The lever 28 comes thereby again in contact with the rod 31 which then causes the nose 50 to disengage the cam 27. At the same time the spring 44 moves the hinged tool holder 6 back into the original position, that is the position shown in Fig. 4.

What I claim is:

1. In a gear-cutting machine, the combination with a constantly moved ram, of a tool holder hinged to said ram and means adapted to swing said holder backward between succeeding cutting operations each lasting several tool strokes and keep the holder in this position until a cutting operation is restarted, substantially as described.

2. In a gear cutting machine, means to reciprocate the cutting tool, means to impart a backward movement to the tool during each stroke of the latter in one direction, and means to alter the extent of backward movement of the tool at a predetermined 125 number of strokes of the latter, whereby the tool is moved out of cutting position.

3. In a gear cutting machine, means to reciprocate the cutting tool, means to impart a backward movement to the tool during 130

each stroke of the latter in one direction, and means to increase the extent of backward movement of the tool at a predetermined number of strokes of the latter, whereby the tool is moved out of cutting position.

4. In a gear cutting machine, the combination with a movable work holder, a constantly reciprocating ram, and a tool holder hinged to the latter in operative relation to the work holder, of mechanisms to swing the holder through arcs of different lengths during different steps in the operation of the machine.

5. In a gear-cutting machine, the combination with a constantly moved ram, of a tool holder hinged to said ram, means adapted to swing said holder backward between succeeding cutting operations and keep it in this position until a cutting operation is restarted, a central drum and means controlled by the latter adapted to initiate the starting of said backward swinging movement of the hinged tool holder, substantially as described.

6. In a gear-cutting machine, the combination with a constantly moved ram, of a tool holder hinged to said ram, a cam-disk shaft adapted to actuate said ram, means for driving the shaft, means operatively connecting said cam-disk shaft to means adapted to swing the hinged tool holder backward between succeeding cutting operations, a control drum, means operatively connecting the drum to the cam-disk shaft and means acted upon by said control drum adapted to initiate the starting of said backward swinging movement of the tool holder, and locking means, influenced by the means acted upon by the control drum, to prevent a forward swinging movement of said holder until a cutting operation is restarted, substantially as described.

7. In a gear-cutting machine, the combination with a constantly moved ram, of a tool holder hinged to said ram, mechanism operatively connected to said holder having the tendency to swing said holder in a forward direction, a movable member adapted to actuate said mechanism in a backward direction, a spring acting upon the movable member, and means adapted to move said member between succeeding cutting operations against the action of its spring for the purpose of swinging the hinged holder backward, said means being also adapted to keep said member in the shifted position until a cutting operation is restarted, substantially as described.

8. In a gear cutting machine, the combination with a ram, of a tool holder hinged to said ram, a cam-disk shaft adapted to

constantly move said ram, mechanism operatively connected to said holder and having the tendency to swing the latter in a forward direction, a member adapted to move said mechanism in a backward direction, a spring acting upon said member, a shaft adapted to be oscillated by said cam-disk shaft, a cam-disk fixed to the oscillatory shaft, a lever loosely mounted on the latter and adapted to move said member against the action of its spring for the purpose of swinging the tool holder backward, a pawl on said lever adapted to engage said cam-disk, a control drum driven by said cam-disk shaft, a rod resting on said control drum, a member connected to said pawl and engaged by the rod, the latter being adapted to control the engagement of the pawl with the cam disk by effecting a movement of the member connected to the pawl, and means adapted to keep said member in the shifted position until a cutting operation is restarted, substantially as described.

9. In a gear cutting machine, the combination with a ram, of a tool holder hinged to said ram, a cam-disk shaft adapted to constantly move said ram, mechanism operatively connected to said holder having the tendency to swing said holder in a forward direction, a member adapted to move said mechanism in a backward direction, a spring acting upon said member, a shaft adapted to be oscillated by said cam disk shaft, a cam-disk fixed to the oscillatory shaft, a lever loosely mounted on the latter and adapted to move said member against the action of its spring for the purpose of swinging the tool holder in a backward direction, a pawl on said lever adapted to engage said cam disk, a control drum driven by said cam-disk shaft, a rod resting on said control drum, a member connected to said pawl and working together with the rod, which is adapted to control the engagement of the pawl with the cam disk by effecting a movement of the member connected to the pawl, a collar fixed to the last mentioned rod and a locking mechanism adapted to work together with said lever for the purpose of keeping the member acted upon by a spring in the shifted position until a cutting operation is restarted, said collar being adapted to effect the release of the lever by acting upon the locking mechanism, substantially as described.

In testimony that I claim the foregoing as my invention, I have signed my name in presence of two subscribing witnesses.

MAX MAAG.
